UNITED STATES PATENT OFFICE.

WINFRED M. BROOKS, OF SOUTH ORANGE, NEW JERSEY.

SEALING MEANS.

Application filed August 6, 1921. Serial No. 490,213.

To all whom it may concern:

Be it known that I, WINFRED M. BROOKS, a citizen of the United States, and a resident of South Orange, in the county of Essex, State of New Jersey, have invented certain new and useful Improvements in Sealing Means, of which the following is a specification.

This invention relates to shackle seals or the like for sealing the hasps of freight car doors or the like in such a way as to indicate, upon inspection, when tampering with the seal has occurred.

In Patents Nos. 1,354,164 and 1,380,038 a shackle seal of the general character employed is disclosed, the construction involving a shackle that is interlocked with itself and a tell-tale lug for sealing the device in such a manner that when the lug is unbent the metal composing it is fractured thus revealing the attempt to gain access to the contents of the car or container as the case may be. While the sealing member as shown in these patents is effective in the manner stated therein, unscrupulous persons have found a way of circumventing the sealing device. It will be noted that in these patents the loop formed by the shackle is relatively large, that is: there is an absence of means for drawing the device tight against the hasp. Unscrupulous persons have therefore at times severed the shackle, leaving the seal intact, and after rifling the contents of the car or package have replaced the shackle in the hasp and have hidden the severed part of the shackle in the hasp in such way that detection would not take place upon a careless or casual inspection of the parts.

It is the main object and feature of this invention to provide means whereby the shackle and sealing member may be drawn snugly into engagement with the hasp to thereby prevent the restoration of the seal from being simulated.

In the accompanying drawings the invention is disclosed in several concrete and preferred forms, in which—

Fig. 1 is a general view showing the sealing device applied to the hasp of a car, with the sealing member in locked position.

Fig. 2 is a plan view showing the sealing device before use.

Fig. 3 is a plan view showing the free end of the shackle threaded through the seal-

ing member with the latter in its open position.

Fig. 4 is a plan view of a detached shackle that may be used in one form of the invention.

Fig. 5 is a plan view of a modified form of sealing member.

Fig. 6 is an edge view of the parts shown in Figs. 4 and 5, one end of the detached shackle having been inserted in the detached sealing member and anchored there.

Fig. 7 is a plan view of Fig. 6 showing the free end of the shackle slidingly inserted in the sealing member.

1 indicates the shackle preferably of ribbon-like flexible material such as sheet metal or paper and 2 is the sealing member. 3 is the hasp or other element to which the sealing device is to be attached. In Figs. 1, 2 and 3 one end of the shackle is anchored to the sealing member 2 by rivet 4 or otherwise, while in Figs. 4, 5, 6 and 7 the shackle 1^a is detached from sealing member 2^a. In the latter case one end of the shackle is anchored on the sealing member by inserting it in the guide 5^a of the sealing member and by banding the shackle as at 1^b after insertion.

One end of the shackle being anchored, the other end thereof is passed through the hasp, is then doubled back as shown in Figs. 3 and 7 and inserted into guide 5 (Fig. 3) or 5^a (Fig. 7) of the sealing member. The free end of the shackle is slid through said guide until the shackle and sealing member are brought snugly against the hasp, after which the sealing member is bent back upon itself in the plane of the guide and shackle as shown in Fig. 1. The loop formed by the shackle is therefore not large enough to admit of severance without detection.

The sealing member may be of different construction. In Figs. 1, 2 and 3 an oblique guide 5 is formed by opposed prongs 6, 7 and 8, this configuration being followed in this instance because it permits of a more gradual bending of the shackle. Prongs 6 and 7 are located at one side of neck portion 9 and prong 8 at the other side thereof. This neck portion constitutes a weakened zone and may be notched as at 10 to definitely mark the bending point and to adequately weaken the material. It will be understood that when it is attempted to un-

bend the sealing member the material thereof will be fractured.

In Figs. 5, 6 and 7 the sealing member 2^a is formed with a guide 5^a composed of opposed prongs 11 and 12 on either side of neck portion 13. This neck portion may also be notched as at 14.

I claim:

1. A shackle seal or the like comprising: a shackle of flexible material, and a sealing member of sheet material on which one end of the shackle is anchored and having a guide open at both ends to slidably receive lengthwise the other end of the shackle; said sealing member being bent back upon itself in the plane of the guide and shackle to prevent sliding movement of the shackle.
2. A shackle seal or the like comprising: a shackle of flexible material, and a sealing member of sheet material on which one end of the shackle is anchored and having a guide open at both ends to slidably receive lengthwise the other end of the shackle; said sealing member having a weakened zone in the plane of the guide and shackle along which it is bent to prevent sliding movement of the shackle and to seal it, the material of said member being fractured when unbending it.
3. The combination with a hasp or the like of a shackle seal, adapted to be drawn tight around the parts of the hasp, comprising: a sealing member of sheet material having a guide open at both ends to slidably

receive lengthwise a shackle, and a shackle of flexible material having one end anchored on the sealing member and its other end passed through the hasp and through the guide of the sealing member, to thereby draw the sealing member and shackle into snug engagement with the hasp; said sealing member being bent back upon itself in the plane of the guide and shackle to prevent sliding movement of the shackle.

4. A shackle seal or the like comprising: a sealing member of sheet material having an intermediate neck portion and opposed prongs adjacent said neck portion forming a guide open at both ends, and a shackle of flexible material having one end anchored on the sealing member and its other end slidably lengthwise through the guide, said sealing member being bent back upon itself at the neck portion thereof.

5. A shackle seal or the like comprising: a sealing member of sheet material having an intermediate neck portion and opposed prongs adjacent said neck portion forming an oblique guide open at both ends, and a shackle of flexible material having one end anchored on the sealing member and its other end slidably lengthwise through the guide, said sealing member being bent back upon itself at the neck portion thereof.

Signed at New York city, in the borough of Manhattan, county and State of New York, this 4th day of August, 1921.

WINFRED M. BROOKS.
